UNITED STATES PATENT OFFICE.

DUNCAN MACMILLAN, OF BROOKLYN, NEW YORK, ASSIGNOR OF ONE-HALF TO HERMAN D. MYERS, OF CANTON, OHIO.

STRAP-FASTENING.

No. 903,100.

Specification of Letters Patent.

Patented Nov. 3, 1908.

Application filed October 1, 1907. Serial No. 395,431.

To all whom it may concern:

Be it known that I, DUNCAN MACMILLAN, a citizen of the United States, residing at Brooklyn, county of Kings, State of New York, have invented certain new and useful Improvements in Strap-Fastenings, of which the following is a full, clear, and exact description.

This invention relates to strap end fastening devices, and more particularly to such fastenings as are used on harnesses.

It is my purpose to provide a fastening device which is simple in structure, inexpensive to manufacture, and is easily secured in place.

Among the advantages of this device are,—the desired connection is readily made; a pull in either direction tends to make the fastening more secure; it is readily adjusted or detached; it is particularly useful on breeching tugs on harnesses, to prevent the tail of the horse from catching, and dispenses with all separate guard-plates or shields, which in the past have performed no other function than that of guarding the buckle from the tail.

While I have shown my invention as applied to the support for a breeching tug, it is to be understood that the same may be applied as well wherever two strap ends are to be detachably secured, and while showing the device in the preferred form, changes may be made in detail without departing from the scope of my invention.

In the drawings—Figure 1 is a view in side elevation of the complete fastening; Fig. 2 is a plan view of the same; Fig. 3 is a view in central longitudinal section through the fastening device; Fig. 4 is a view similar to that shown in Fig. 3, showing a modification thereof.

1 and 2 are the strap ends to be secured together.

3 is a breeching ring. The end 2 is doubled upon itself, as shown, and the loop thus formed holds the cam shield. The cam shield comprises a slightly arched top member 4, side members 5 depending centrally

from each side and connected below the shield by a bearing pivot 6.

7 is a locking-stud or tongue extending upwardly through and above the strap end 2.

8 is the flanged portion or base on the stud 7, adapted to be held between the doubled portions of the strap to secure the stud 7 in place. The strap 1 is provided with the usual perforations 9, of a size to pass over the stud 7.

10—10 are tuck loops on the strap end 2.

The operation is as follows: The strap 1 is slid under the arched cam shield, then over the locking-stud 7, until the proper adjustment is made; and then the end is passed under the tuck loops 10 and the perforation 9 is pressed down over the locking-stud 7, and a pull on both strap ends completes the operation. The strain in use is such that the cam shield 4 always engages the strap 1 and presses it down firmly over the stud 7. As both ends of the cam shield always press tightly against the strap 1, no projections are presented to catch a horse's tail, or to catch any object passing.

In Fig. 4 I have shown a slight modification, in which the under side of the shield 4 is recessed at 11, to allow the stud to project slightly above the surface of the strap end 1.

When it is desired to adjust or disconnect the straps, it is merely necessary to swing back the cam shield, lift the eyelet 9 from the locking-stud 7 by an upward pressure on strap 1, withdraw the end from tuck loops 10, and then pull out or adjust the strap, as desired.

What I claim is—

1. In a device of the character described, the combination of a strap, a cam shield thereon, and a locking-stud independently mounted on said strap, projecting above said strap and directly under one end of said shield.

2. In a device of the character described, the combination of a strap, a swinging solid cam shield mounted intermediate its length thereon and having a recess on the under

side at one end; a locking-stud projecting above said strap and directly under one end of said shield and adapted to enter said recess.

5 3. In a device of the character described, the combination of a strap, a locking stud projecting upwardly therefrom, and a solid cam shield mounted to swing upon said

strap one end passing over said stud, and having a recess on the under side of the 10 shield having a shoulder adapted to engage the said stud.

DUNCAN MacMILLAN.
